UNITED STATES PATENT OFFICE.

DAVID WIGERT, OF GALESBURG, ILLINOIS, ASSIGNEE TO DAVID WIGERT BOILER WORKS, OF GALESBURG, ILLINOIS.

BOILER CONNECTION.

1,071,287.

Specification of Letters Patent. Patented Aug. 26, 1913.

Original application filed October 12, 1912, Serial No. 725,547. Divided and this application filed January 9, 1913. Serial No. 741,072.

To all whom it may concern:

Be it known that I, DAVID WIGERT, a citizen of the United States, residing at Galesburg, in the county of Knox and State of Illinois, have invented a new and useful Boiler Connection, of which the following is a specification.

This invention relates to boilers and more particularly to means for connecting water pipes to headers and the like.

One of the objects of the invention is to provide a novel form of nut for use in assembling the pipes, said nut being hollow and constituting a container for portions of the water being heated whereby increased heating surface is produced and the connections are prevented from burning off when subjected to the heat in the furnace.

The device is more particularly a division 20 of an application filed by me in the United States Patent Office on October 12, 1912, said application bearing Serial No. 725,547.

The invention consists in the combination and arrangement of parts and in the details 25 of construction hereinafter described and claimed, it being understood that changes in the precise embodiment of the invention herein disclosed, can be made within the scope of what is claimed, without departing 30 from the spirit of the invention.

In the accompanying drawings the preferred form of the invention has been shown.

In said drawings:—Figure 1 is a side elevation of a portion of a furnace, one side wall and the parts connected thereto being removed, and the top of the casing being shown in section. Fig. 2 is a section on line A—B Fig. 1. Fig. 3 is an enlarged section 40 through one of the devices employed for coupling a pipe to a header.

Referring to the figures by characters of reference 2 designates the hollow front of the boiler, the same being so shaped as to provide fuel openings and ash openings at the proper points. As shown, each side wall of the boiler may include a front end section 5, a desired number of intermediate sections 6, and two back end sections 7 and 50 8. All of the sections are hollow and, each of the sections 5, 6, 7 and 8 is provided upon its sides and adjacent its upper and lower

ends, with tubular connections 10 whereby communication between the sections is maintained.

Arranged adjacent the inner side of section 7 is a header 25 provided in its back wall with a desired number of openings 26 disposed preferably in staggered relation. This header is in communication with the 60 sections 7 through push nipples 27, there being a tie rod extending axially through the nipples for the purpose of binding the sections 7 and the header 25 upon the push nipples.

Fitted within each of the openings 26 is the tapered intermediate portion 28 of a hollow coupling member 29, fitted in any desired manner, upon the upper end of a grate pipe 29', this pipe extending downwardly below the header 25 and thence forwardly. The coupling member 29 has its outer or exposed end closed, as shown particularly in Fig. 3 while its other end, which is located inside of the header 25, is open. 70 Thus water may freely circulate from pipe 29' through coupling member 29 to the header 25 and vice versa.

Fitted within the header wall and directly opposite each opening 26, is the cylindrical portion 30 of a hollow nut 31. One end of this nut is preferably reduced in diameter and provided with a threaded bore 32 for the reception of one end portion of a bolt 33. This bolt is arranged axially 80 within the coupling 29 and engages the closed end of the coupling. A flange 34 is formed upon the nut 31 and is adapted to be seated within a counter bore 35 formed in the front face of the header 25. One or 90 more openings 36 are provided within that portion of nut 31 projecting into the header 25 and water is thus free to circulate from the header and into and out of the nut 31. Obviously, therefore, all danger of the nut 95 burning off under the intense heat to which it is subjected is eliminated.

As hereinbefore stated, the openings 26 are preferably disposed in staggered relation and, therefore, the couplings 29 are 100 similarly arranged. Furthermore, the couplings constituting the upper row are preferably of greater length than those constituting the lower row, as will be seen by referring

ring particularly to Fig. 1. Thus the pipes 29' extending from the upper couplings 29 will not lie too close to the pipes extending downwardly from the couplings of the lower 5 row.

As hereinbefore pointed out, pipes 29' extend forwardly under the header 25. These pipes thus constitute hollow grate bars and the front ends of the pipes are attached to 10 couplings 37 similar to the couplings 29 hereinbefore described. These couplings 37 are connected to a header 38 supported in any suitable manner within the front portion 15 of the boiler and having a supply pipe 39 opening thereinto.

Arranged along the inner side of each section 6 are two parallel pipes 40 the lower 20 ends of which are connected to the lower portions of the sections 6 by means of couplings 41. The upper ends of the pipes 40 are disposed parallel with the overhanging portions of the sections 6 and then extend upwardly and are attached to the upper portions 25 of the sections by means of couplings 42. Each of the sections 5 is provided with but a single pipe 43 this pipe, however, being similar to the pipes 40 and being similarly connected to their sections.

As hereinbefore stated, the particular construction of the coupling used for securing the pipes to the header is of especial importance. Heretofore when nuts and bolts have been used for similar purposes, the nuts have soon burned off under the intense heat to 35 which they have been subjected and the parts have thus become separated, thereby rendering the boiler unfit for further use until repaired. It has been found that by 40 using hollow nuts communicating with the interior of the header, the water admitted to the nuts will prevent them from burning

off. Then too, considerable heating surface is thus added to the boiler.

What is claimed is:

1. In a boiler the combination with a wa- 45 ter containing element, of a water conducting pipe, a coupling member connected to one end of the pipe and discharging, at one end, into said element, a fastening bolt ex- 50 tends from said member and through the water containing element, and a hollow nut 55 engaging said bolt and bearing against the water containing element, the outer end of the nut being closed and there being an aperture within the nut for establishing communication between the interiors of the nut and the water containing element.

2. In a boiler, the combination with a header, and a water conducting pipe, of a hollow coupling member mounted upon the 60 pipe and projecting into and communicating with the interior of the header, a bolt 65 extending from said member and into the header, and a hollow water containing nut 70 engaging the bolt and opening into the header.

3. In a boiler, the combination with a wa- 75 ter containing element, of a hollow nut having an open end projecting into the said ele- 70 ment, a hollow coupling member projecting into said element and having an open end discharging thereinto, a bolt connected at its ends to said member and to the nut, and a water conducting pipe connected to the cou- 75 pling member.

In testimony that I claim the foregoing as my own, I have hereto affixed my signature in the presence of two witnesses.

DAVID WIGERT.
